ABSTRACT: A ready to use paint pourer is offered as a practical aid when the user desires to pour paint from one container into another container in a spillproof manner. Each of the two forms herein shown comprises a self-contained moldable plastic attachment characterized by an auxiliary lid which is brought into use after the regular closing lid has been pried loose and removed from the keying channel of the annular mounting rim. This auxiliary or replacement lid has (1) a suitable spout and (2) marginal attaching and retaining means having a web whose outer peripheral edge is provided with an inverted channel-shaped adapter capable of being conformingly snapped over the rim's securing bead.

PAINT BUCKET LID WITH POURING SPOUT

This invention relates to certain new and useful improvements in self-contained ready to use pourer attachments for containers such as for example, paint cans and buckets and has to do with a pourer embodying a suitably angled spout constituting an integral component of a specially designed lid which can be effectually fitted and mounted on the usual annular channeled bead-equipped lid anchoring rim with which the upper openable end or mouth of the container provided.

As will be hereinafter more fully set forth, the instant disclosure has to do with two forms or embodiments of the overall concept. To the ends desired the subject matter of this invention will be comprehended both broadly and specifically and should be construed accordingly.

Generically, the disclosure covers a paint pourer attachment, that is, an attachment which lends itself to economical and feasible production from flexible and resilient self-adapting plastic material. Briefly, the inventive idea comprehends the utilization of a readily applicable and removable cover, more particularly, a replacement lid which is auxiliary to the main or conventional lid and which is applicable to the built-in lid-mounting rim. This auxiliary lid is equipped with an oblique angled spout and has an outer marginal edge portion provided with attaching and retaining means. This latter means embodies a web which can be semicircular in plan or completely annular and of prescribed ready to use diameter. This web constitutes a protective shield or guard in that it is adapted to bridge over and cover the channel of the mounting rim whereby to prevent paint from filling and objectionably clogging the channel. The outer peripheral edge is provided with a resilient snap-fit retainer, said retainer being channel shaped in cross section and designed and adapted to retentively snap over said bead and cooperate with said shoulder in a manner to locate and retain said attachment in its ready to use pouring position.

One embodiment of the invention is characterized by a semispherical hood. This hood is approximately one-half the diameter of the open mouth or upper end of the bucket or can. When it is applied it overhangs and occupies a plane above the plane of the rim at the open top of the bucket. The underneath or concave side of the lid provides a receiver or receptacle into which the outflowing paint is funneled and is capable of being readily directed to and discharged by way of the spout. This form of the invention is of one-piece moldable plastic material. The attaching and retaining means is pliant and capable of being snapped and lodged in place by hand pressure on rims of slightly varying sizes.

The other form of the invention is characterized by a disk or an equivalent discoidal diaphragm. The diaphragm is of a diameter to span the part of the bucket opening which is intended to be covered when the attachment is in use. The attaching and retaining means corresponds to that used on the hood-type lid. A vent is provided and a stopperlike plug can be utilized in a manner to close the vent when it is not being used.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a view in perspective showing a fragmentary portion of a paint-containing can or bucket with the usual or customary closing lid removed and with the attachment lid substituted therefor in a manner to provide the desired paint trapping, funneling and pouring spout.

FIG. 2 is a section taken approximately on the plane of the section line 2-2 of FIG. 1.

FIG. 3 is a sectional view at right angles to FIG. 2, that is a view observing FIG. 2 in a direction from left to right.

FIG. 4 is a view on a smaller scale with the attachment completely detached and readied for use.

However and with the flexible attaching and retaining means 34 herein shown it will be evident as suggested in FIG. 5 how this semicircular-type hood and retaining means lends itself to variable usage. In those cases involving paint containers ranging from pints, quarts and gallons it will be evident that it may be necessary to provide prescribed sizes for different makes or sizes of cans and buckets. It is also within the purview of the invention that the form of the invention herein shown can be sold either to paint manufacturers or to companies that make paint cans and paint buckets. It might well be the practice to employ this type of attachment as a giveaway item if this manner of commercialization is established.

With reference now to the embodiment of the invention shown in FIGS. 6 to 9 it will be evident in FIGS. 6 and 7 that the bucket 50 comprises a suitable container of requisite capacity or size which is denoted at 52. The bucket has the same structural characteristics as already described in that it is provided with a lid-mounting rim 54 having a channel 56 the inner short vertical wall of which is provided with a horizontal or lateral reinforcing lip 58. The outer wall 60 (FIG. 7) is joined with an inverted channel-shaped bead 62 which is secured over the edge of the container in the usual manner. The pourer in this form of the invention is denoted by the numeral 64 in FIG. 8 in particular. It comprises a plastic disk also referred to as a discoidal replacement lid 70. The lid is of suitable diameter for the can shown. The attaching and retaining means comprises an inverted outer channel 72 which has a turned-in lip 74 engaging beneath the shoulder on the bead 62 as shown amply in FIGS. 7 and 9. The outer marginal portion which is here designated as the web is denoted at 76 and again its purpose is to span and shield or guard the upwardly opening channel 56. The depending flange 78 is spaced inwardly from and is concentric with the downwardly opening channel 72. This flange is of requisite vertical cross section and is constructed to cooperatively engage the aforementioned lip 58. It may be necessary to accommodate different sizes to provide the flange 78 with an upper encircling rib 80 and a similar lower encircling rib 82. It is believed that this provision of dual ribs adapts the flange 78 to cooperate either with the lower rib 82 attached or the upper rib attached in a suitably accommodating manner (not detailed). With reference again to FIG. 8 it will be noted that 84 designates a vent to accommodate a pluglike stopper 86. This stopper or plug is on the outer free end 88 of a flexible tab or strap 90 having an inner apertured end detachably connected with the headed shank 92 on the horizontal limb 94 of an L-shaped bracket 96. The vertical limb of the bracket is denoted at 98. This bracket serves not only to accommodate the button-down tab or strap but provides, as is evident, an accessible finger grip which may necessarily have to be resorted to in detaching the attachment lid 70. In this form of the invention the discharge opening is denoted at 100 and the integral diagonally disposed pouring spout at 102. The outer end of the spout is normally closed by an attachable and detachable closing cap 104.

The views of the drawings have been chosen to independently and generically disclose the overall subject matter of the invention. The matter of using the domical or hood-type pourer 28 is shown in FIGS. 1 to 5 inclusive. The construction and manner of use of the second form of the invention is adequately shown in FIGS. 6 to 9. The simplicity of construction is such that all significant aspects of the overall concept should be and are self-evident. Accordingly, a more extended description is deemed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling

within the scope of the invention as claimed.

What I claim as new is as follows:

- 5 1. A paint pourer attachment capable of replacing the usual pry-off lid on an annular lid-mounting rim of a paint bucket, said attachment comprising a replacement lid which is applicable to said annular rim when the regular lid is detached and temporarily set aside and provided with a concavo-convex hemispherical hood, said hood being adapted to overhang the receptacle portion of the paint bucket when in use and the concave underneath side thereof providing a paint trapping and concentrating funnel capable of directing paint to an opening provided in said hood, said hood having a dispensing spout communicating with said opening and projecting beyond the convex surface of said hood, the outer marginal 10 bottom portion of said hood being provided with hood attaching and retaining means, said means embodying a flat web which is semicircular in plan and of uniform cross-sectional thickness and of a width that it constitutes a shield, said shield being adapted to reside flatwise atop and bridge over said 15 mounting rim and the channel portion thereof, said web having an outer peripheral edge provided with an elevated resilient snap-fit retainer which is channel shaped in cross section and designed and adapted to retentively snap over a bead which marginally encompasses said rim, the outer wall of said 20 channel having a turned-in lateral lip releasably engageable with a coacting shoulder portion on said bead, said web having an inner peripheral edge provided with a depending flange terminating at its bottom in an outwardly directed lip capable of being releasably interlocked with a cooperating lip on an inward wall of the channel of the aforementioned rim.
- 25 30 2. For use on a paint bucket having an openable top provided with an annular lid-mounting rim having a lid-keying channel overhanging the bottom of the bucket and a concentric encompassing bead fixed and providing an exterior overhanging shoulder, a readily applicable and removable paint pourer attachment capable of replacing the usual bucket closing lid, said attachment comprising an auxiliary replacement lid provided with a dispensing spout alignable and communicable with the receptacle portion of said bucket, said auxiliary lid having an outer marginal portion provided with attaching and retaining means, said means embodying a web providing a shield, said shield adapted to bridge over and cover the channel of said mounting rim, said web having an outer peripheral edge provided with a resilient snap-fit 35 retainer, said retainer being channel shaped in cross section and designed and adapted to retentively snap over said bead and cooperate with said shoulder in a manner to locate and retain said attachment in its ready to use pouring position, said auxiliary lid comprising a semispherical hood overhanging and occupying a plane above the open top of said bucket, the underneath concave side of said lid cooperating with the receptacle portion of the bucket and mounting rim and defining a paint-concentrating funnel capable of directing paint into the dispensing spout, said attachment being made of one 40 45 50 55 piece of moldable plastic material, said attaching and retaining means being pliant and capable of being snapped and lodged in place by hand pressure and subsequently caught hold of and freed for removal at will, said web being semicircular in plan and having an inner peripheral edge provided with a depending flange commensurate in length with the length of said web, said flange terminating at its bottom in a lateral outwardly directed lip capable of being releasably interlocked with an existing lip on a coacting inward wall of the channel of said lip-mounting rim, said web and said channel-shaped retainer being yieldable when manually spread and being capable of nominal expansion and being possessed of inherent contraction properties in a manner to fittingly and 60 65 70 75 retentively coordinate with lid-mounting rims such as are provided on buckets of slightly varying diameters.
